CLAIM

The ornamental design for a beverage holder, as shown and described.

DESCRIPTION

FIG. 1 is a top, front perspective view of a beverage holder showing our new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof;

FIG. 8 is a cross sectional view, taken along line 8-8 in FIG. 6;

FIG. 9 is an enlarged view of the region identified by the number “9” in FIG. 8 thereof;

FIG. 10 is an enlarged view of the region identified by the number “10” in FIG. 8 thereof; and,

FIG. 11 is an alternate top, front perspective view thereof. The uneven-length broken lines represent unclaimed boundaries of the claimed design.

The even-length broken lines depict portions of the beverage holder that form no part of the claimed design.
